UNITED STATES PATENT OFFICE.

JOHN H. HILTZ AND JOHN B. SMITH, OF DETROIT, MICHIGAN, ASSIGNEES TO CHAMBERLIN METAL WEATHER STRIP COMPANY, OF DETROIT, MICHIGAN.

SWINGING SASH.

No. 872,420.

Specification of Letters Patent.

Patented Dec. 8, 1907.

Application filed July 8, 1907. Serial No. 382,501.

To all whom it may concern:

Be it known that we, JOHN H. HILTZ and JOHN B. SMITH, citizens of the United States, residing at Detroit, in the county of Wayne and State of Michigan, have invented certain new and useful Improvements in Swinging Sashes, of which the following is a specification, reference being had therein to the accompanying drawing.

10 This invention relates to improvements in swinging sashes and has for its primary object the provision of improved means for sealing the space intermediate the border of the sash and the window casing or frame 15 against the admission of dust, moisture, air, etc., and more particularly the space beneath the bottom edge of the sash.

The invention comprehends the provision of a spring metal weather strip interposed 20 between the lower member of the sash frame and the bottom member of the sash secured at one edge to one of said members and having a freely movable projected edge portion to spring behind an oppositely projecting 25 portion of the member to which it is unattached, said portion terminating in a rounded or smooth edge adapted to facilitate the riding of the parts over each other in the closing movement of the sash.

30 A convenient embodiment of the invention embraces the provision of a strip of the character described secured at one edge to the bottom member of the sash and having its inner edge free and projected downwardly 35 and inwardly from the sash, and the bottom member of the sash frame or casing being provided with a portion, for instance, a stop-strip, behind the inner edge of which the free edge of the strip is adapted to spring, and 40 also preferably impinge thereagainst, when the sash is closed, the free edge of the strip terminating in a flange bent upwardly therefrom and projecting into, whereby to play in, a slit or groove in the sash.

45 The novel features in the construction and arrangement of the several parts of our structure will be apparent from the detail description hereinafter contained; when read in connection with the accompanying drawings 50 forming part hereof.

In the drawings, Figure 1 is a perspective view of one corner of a window casing or frame, and the swinging sash hinged thereto, including the weather strip interposed between the same; Fig. 2 is a transverse sec-

tional view through the frame and sash, the sash being shown in closed position; and Fig. 3 is a sectional view transverse through one of the side members of the casing.

Referring more specifically to the drawings, wherein like reference characters designate corresponding parts in the several views, A designates one of the vertical or side members of the frame or casing, B the lower member thereof, C the side of the swinging sash hinged as at D to the member A, and E the bottom member of said sash. The sides and top (not shown) of the sash are grooved as at F for the reception of the sealing flange G of a weather strip H secured to the face of the member A, this particular strip being of a type well known in this art.

Projecting upwardly from the surface of the frame member B, we provide a stop-strip I having at its outer upper edge an inclined metallic insert J for a purpose as will presently appear, said insert being at the end of the stop-strip nearest the hinged edge of the sash.

K represents an inwardly and downwardly turned portion of the spring metal weather strip constituting a characteristic feature of the present improvement. Extending outwardly from said portion and arranged to lie flat upon the bottom surface of the member E of the sash, is a securing portion L tacked to the sash as at M and projected at its edge into a kerf N in the sash, the outer face of the sash having a depending portion O arranged to abut the outer surface of the stop-strip I when the sash is closed. The strip is bent upwardly as at P to provide a rounded or smooth edge Q to facilitate the riding of the same over the stop-strip I, this upwardly bent portion of flange P extending into and having free vertical movement in a groove R formed between the outer surface of the sash and a piece of molding S secured to and constituting a part of the lower member E, of said sash.

When the sash is closed from an open position represented in Fig. 1, the inner corner of the weather strip or edge Q will first come in contact with the inclined surface of the metallic insert J and, owing to the gradual upward inclination of such surface, the strip in riding thereover will be correspondingly elevated, such movement being permitted by the flange P moving vertically in the groove R, until the edge Q is level with

the upper surface of the stop-strip I over which it will ride until projected inwardly therebeyond when the free edge of the strip will spring downwardly behind the inner 5 surface of the stop-strip and forcibly impinge upon the corner or edge thereof, see Fig. 2.

By the arrangement of the parts as hereinabove described, we provide a highly efficient, simple, and durable sealing engagement 10 between the lower member of the window frame or casing and the bottom member of the swinging sash.

I claim:

1. The combination with a window casing 15 and a swinging sash therefor, of a spring metal weather strip interposed between opposite members of the sash and frame and arranged beneath the sash, said strip being secured at its inner edge to one of said members and having a freely movable projected edge portion arranged to be opposed to the direction of the closing movement of the sash, the member to which the strip is unattached having an oppositely projecting portion 20 behind which said freely movable projected edge portion of the strip is adapted to spring when the sash is closed, and said free edge portion terminating in a rounded or smooth edge adapted to facilitate the riding 25 of the parts over each other in the closing movement of the sash.

2. The combination with a window casing and a swinging sash therefor, of a spring metal weather strip interposed between 30 opposite members of the sash and frame, said strip being secured at its inner edge to one of said members and having a freely movable projected edge portion arranged to be opposed to the direction of the closing movement of the sash, the member to which the strip is unattached having an oppositely projecting portion 35 behind which said freely movable projected edge portion of the strip is adapted to spring when the sash is closed, and said free edge portion terminating in a flange bent therefrom and projected loosely into a groove in the member to which it is attached.

3. The combination with a window casing 40 and a swinging sash therefor, of a spring metal weather strip interposed between opposite members of the sash and frame and arranged beneath the sash, said strip being secured at its inner edge to one of said members and having a freely movable projected edge portion arranged to be opposed to the direction of the closing movement of the sash, the member to which the strip is unattached having an oppositely projecting portion 45 behind which said freely movable projected edge portion of the strip is adapted to spring when the sash is closed, and said free edge portion terminating in a flange bent therefrom and loosely associated with the member 50 to which it is attached.

4. The combination with a window casing and swinging sash therefor, of a spring metal weather strip interposed between the bottom members of the sash and frame, said strip being secured at its inner edge to the bottom 70 member of the sash and having a freely movable portion projecting inwardly and downwardly from the sash arranged to be opposed to the direction of the closing movement of the sash terminating in a flange bent therefrom, and the bottom member of the casing having a projecting part behind which the free edge of the weather strip is adapted to spring when the sash is closed. 75

5. The combination with a window casing 80 and swinging sash therefor, of a spring metal weather strip interposed between the bottom members of the sash and frame, said strip being secured at its inner edge to the bottom member of the sash and having a freely movable portion projecting inwardly and downwardly from the sash arranged to be opposed to the direction of the closing movement of the sash terminating in a flange bent therefrom, and the bottom member of the casing 85 having a projecting part behind which the free edge of the weather strip is adapted to spring when the sash is closed, the bottom member of the sash also having a grooved portion in which the flange of the strip projects and may play. 90

6. The combination with a window casing and swinging sash therefor, of a spring metal weather strip interposed between the bottom members of the sash and frame, said strip 100 being secured at its inner edge to the bottom member of the sash and having a freely movable portion projecting inwardly and downwardly from the sash arranged to be opposed to the direction of the closing movement of the sash terminating in a flange bent therefrom, and the bottom member of the casing 105 having a stop-strip behind which the free edge of the weather strip is adapted to spring when the sash is closed. 110

7. The combination with a window casing and swinging sash therefor, of a spring metal weather strip interposed between the bottom members of the sash and frame, said strip being secured at its inner edge to the bottom 115 member of the sash and having a freely movable portion projecting inwardly and downwardly from the sash arranged to be opposed to the direction of the closing movement of the sash terminating in a flange bent therefrom, and the bottom member of the casing 120 having a stop-strip behind which the free edge of the weather strip is adapted to spring when the sash is closed, the bottom member of the sash also having a grooved portion in which the flange of the strip projects and may play. 125

8. The combination with a window casing and swinging sash therefor, of a spring metal weather strip interposed between the bottom 130

members of the sash and frame, said strip being secured at its inner edge to the bottom member of the sash and having a freely movable portion projecting inwardly and downwardly from the sash arranged to be opposed to the direction of the closing movement of the sash terminating in a flange bent therefrom, and the bottom member of the casing having a stop-strip behind which the free edge of the weather strip is adapted to spring when the sash is closed, and the sash having a depending part arranged to abut said stop-strip.

9. The combination with a window casing and swinging sash therefor, of a spring metal weather strip interposed between the bottom members of the sash and frame, said strip being secured at its inner edge to the bottom member of the sash and having a freely movable portion projecting inwardly and downwardly from the sash arranged to be opposed to the direction of the closing movement of the sash terminating in a flange bent therefrom, and the bottom member of the casing having a stop-strip behind which the free edge of the weather strip is adapted to spring when the sash is closed, the bottom member of the sash also having a grooved portion in which the flange of the strip projects and may play, and the sash having a depending part arranged to abut said stop-strip.

10. The combination with a window casing and swinging sash therefor, of a spring metal weather strip interposed between the bottom members of the sash and frame, said strip being secured at its inner edge to the bottom member of the sash and having a freely movable portion projecting inwardly and down-

wardly from the sash arranged to be opposed to the direction of the closing movement of the sash terminating in a flange bent therefrom, and the bottom member of the casing having a stop-strip behind which the free edge of the weather strip is adapted to spring when the sash is closed, the stop-strip having a portion thereof inclined to uplift the weather strip in the closing movement of the sash to permit the strip to ride over the stop-strip.

11. The combination with a window casing and swinging sash therefor, of a spring metal weather strip interposed between the bottom members of the sash and frame, said strip being secured at its inner edge to the bottom member of the sash and having a freely movable portion projecting inwardly and downwardly from the sash arranged to be opposed to the direction of the closing movement of the sash terminating in a flange bent therefrom, and the bottom member of the casing having a stop-strip behind which the free edge of the weather strip is adapted to spring when the sash is closed, the bottom member of the sash also having a grooved portion in which the flange of the strip projects and may play, the stop-strip having a portion thereof inclined to uplift the weather strip in the closing movement of the sash to permit the strip to ride over the stop-strip.

In testimony whereof we affix our signatures in presence of two witnesses.

JOHN H. HILTZ.
JOHN B. SMITH.
